PROCESS FOR THE MANUFACTURE OF
FACSIMILES ON WOODHans Kaufmann, Frankfort-on-the-Main,
GermanyApplication August 16, 1934, Serial No. 740,120
In Germany August 18, 1933

1 Claim. (Cl. 41—22)

The invention concerns the production of facsimiles, for example of knotted wood effects, pictorial representations and the like on wood surfaces, in connection with colour carrying transfers, 5 parent sheets of cellulose derivatives, such as, for example, cellulose hydrate or acetylcellulose which are extensively employed in trade under the name of "Cellophane" or "Cellon" respectively.

- 10 It is already known, in the production of facsimiles of every kind on wood surfaces to produce on the latter the desired decorations by the known metachromotype process by which transfers are made with the help of a paper covered 15 with a rice-gum-layer. The products obtained in this way possess, in general, the property of forming smooth edges when cut, which means they do not exfoliate at the cut edges. The production is apart from certain difficulties due to 20 the representation vehicle, to a certain extent detailed and leads generally, due to the necessary transfer of the representation from its vehicle to the wood surfaces, to the injury of the definition of printing of the representation. It has also 25 previously been proposed in order to obtain brilliant and permanent colour-coatings, to cover the base with sheets, for example to lay on a groundwork of wood, the desired representations such as photographs, etc., on their reverse side 30 and to fasten them down firmly thereon by means of a covering of pyralin sheet or the like. The fixing down is carried out either by wetting the picture with alcohol or any other liquid in which the sheets chosen are soluble, and thereupon sub- 35 mitting the whole to pressure, or by employing only pressure and heat.

For the decoration of woods which are to be used as objects of utility such as the production of pictures, furniture or the like, such processes 40 are not suitable, for failing a perfect combination of the inlaid representation pressed onto the wood-surface, by the covering sheet, slight breaks in the covering layer lead to immediate destruction, whilst the results produced by such 45 a means of decoration are not technically and economically suitable for the advantageous production of facsimiles for the purposes mentioned above. It has also already been proposed to treat 50 suitable bases such as leather, metal or pliable wood sheets with shining covers or also facsimiles in such a way that the base to be operated on is covered with sheets under the influence of heat or pressure, which, if necessary, can carry 55 imprinted colours, so that one of the glass-clear

representations covered by a sheet can be affixed to the wood base or the like.

This process possesses in contradistinction to the afore-mentioned metachromotype process the advantage of greater simplicity in operation, 5 but shows in contradistinction to the product thus obtained, the serious disadvantage that the facsimiles produced only adhere lightly to the base and especially by the cutting of surfaces thus handled a slight exfoliating of the decorative layer and sheet takes place. Endeavours have been made to overcome this disadvantage, by covering the wood surface with lacquer by pressing a further thin transparent sheet onto the wood surface before putting on the colour 15 bearing sheet. But in these cases also a comparatively slight exfoliation was visible, quite apart from the fact that in consequence the useful advantages in comparison with the metachromotype process were lost.

It has now been found according to this invention that facsimiles can be obtained with especially remarkable adhesive properties and without any injury to the printing definition, on wood surfaces, if the wood to be decorated is subjected 20 to a heat treatment at temperatures lying above 80° C. and the sheets provided with the colouring layer, are affixed immediately after the heating process onto the suitable smoothly polished upper surface while avoiding an absorption of a 25 humidity through the wood pores, and pressed under the application of pressure and heat onto the upper surface.

It has been ascertained that the resistance to 30 scratching, production of smoother cutting edges and security against exfoliation of the facsimiles 35 produced in this way are positively increased as compared with the facsimiles produced according to the known process and thereby the operative process itself in comparison with that of metachromotype is substantially simplified, quite apart 40 from the fact that the products produced according to the process of the invention are especially distinguished by the clarity and exactness of the reproduction in contradistinction to those of all 45 known processes.

The accompanying drawing illustrates in a perspective view an example of a transparent sheet and a wooden base assembled through the process as per the invention, a portion of the sheet being 50 lifted for the purpose of showing its underside. 1 is the wooden base having a polished surface 2, which is to be decorated. The transparent sheet 3 with the ornamentation 4 on its lower side is 55 pressed onto the surface 2 under the application 55

of pressure and heat immediately after the wood base had been subjected to a heat treatment above 80° C.

5 A pretreatment of the wood, apart from a requisite polishing of the surface to be decorated, is absolutely unnecessary. The heat treatment itself can be carried out in any desired manner, such as for example in a drying oven, in a vacuum container kept at the requisite temperature, 10 in a vacuum drying coil as conventionally used in the heat treatment of wood, or the like, so long as care is taken that the benefit obtained from the heating room is not lost by the possibility of an absorption of atmospheric moisture immediately before the pressing of the sheets.

15 The production of smoothly cut surfaces makes possible the use of facsimiles also for the production of the finest tarsia-work pictures or the like, as also the preservation of the definition of printing in the employment of the process of decorating with the finest patterned representations. Durable picturesque representations are especially made possible in the most varied tone tints. The heat treatment according to the invention is 20 not a replacement of the natural drying of the wood in the afore-mentioned process. There can have taken place, for instance, in addition to the employment of the heat treatment according 25

to the invention, one or more pre-drying treatments of the wood, for instance to drive off large proportions of moisture picked up in storage. If desired a preliminary pre-drying can be omitted and the chief drying of the wood carried out at the same time as the heating treatment which immediately precedes the application of the sheets.

For carrying out the heat treatment according to the invention temperatures not much above 80° C., for example up to 90° C., are, in general, sufficient. If desired, however, much higher temperatures may be used which in the first place, for instance, ensure that the moisture content of the work-room does not provide an especially strong 10 tendency for the re-absorption of air moisture. 15

What I claim is:—

A process for the production of facsimiles on wood comprising heating the wood to be treated to a temperature of at least 80° C., immediately 20 thereafter, before the wood is able to absorb moisture from the air, applying to the smooth surface of the wood a colour-containing transparent sheet of a cellulose derivative, and pressing the said sheet on to the wood surface under the application of heat and pressure. 25

HANS KAUFMANN.
